VENTILATOR

Philip Herman, Bethlehem, Pa.

Application July 10, 1939, Serial No. 283,658

2 Claims. (Cl. 98—99)

The invention relates to a ventilator and more especially to a window ventilator.

The primary object of the invention is the provision of a ventilator of this character wherein the same enables ventilation to a room or enclosure without liability of rain, sleet, or the like, entering the room or enclosure and, at the same time, avoiding direct draft upon the occupants of such rooms or enclosures, the ventilator being also used as a screen for the window opening to exclude insects or the like.

Another object of the invention is the provision of a ventilator of this character wherein a slide is arranged so that the ventilator can be regulated to exclude the passage of air therethrough or to enable increased or diminished ventilation at the option of a user.

A further object of the invention is the provision of a ventilator of this character wherein the same involves a construction that enables the easy fitting thereof within a window casement and also its removal therefrom, the said ventilator being of a construction to assure the proper fitting of the same in a window casement within reasonable limits of sizes thereof.

A still further object of the invention is the provision of a ventilator of this character which is simple in its construction, thoroughly reliable and efficient in operation, strong, durable, readily and easily adjusted, and inexpensive to manufacture.

With these and other objects in view, the invention consists in the features of construction the combination and arrangement of parts as will be hereinafter fully described in detail, illustrated in the accompanying drawings, and pointed out in the claims hereunto appended.

In the accompanying drawings:

Figure 1 is an elevation of the ventilator constructed in accordance with the invention.

Figure 2 is a sectional view taken on the line 2—2 of Figure 1 looking in the direction of the arrows.

Figure 3 is a view similar to Figure 1 looking toward the opposite side of the ventilator and partly in section.

Figure 4 is an enlarged sectional view taken on the line 4—4 of Figure 1 looking in the direction of the arrows.

Figure 5 is a mutilated perspective view of one of the extensible end members of the ventilator.

Figure 6 is a perspective view of the adjustable slide for the ventilator.

Similar reference characters indicate corre-

sponding parts throughout the several views in the drawings.

Referring to the drawings in detail, A designates generally the ventilator in its entirety and involves an open frame including end rails 10, bottom rail 11 and top rail 12, respectively, these at their meeting ends being united in any suitable manner, while the innermost edge of the bottom rail 11 is formed with an outwardly inclined or sloping face 13 for a purpose presently described.

Fitting the end rails 10 and slidably telescoped thereover as well as portions adjacent thereto of the bottom and top rails 11 and 12 are extensive wings or end pieces 14, these being preferably made from sheet metal of the shape disclosed in detail in Figure 5 of the drawings.

These wings or pieces 14 are adjustably held engaged therewith a frame, that is to say the end rails 10 thereof, by screws 15 which engage in elongated slots 16 provided in opposite sides of the said wings or pieces 14 and fixed in the said frame. Counterseated in the end rails 10 and concealed within the wings or pieces 14 are coiled compression springs 17 which play against the closed outermost edged portions 18 of said wings or pieces 14 so that these will be maintained under tension. In this manner through the use of the wings or pieces 14 the frame can be removably interfitted within a window casement or the like preferably engaged in the sash guide- ways therein.

Arranged with relation to the open center 19 of the frame including the rails 10, 11 and 12, and opposite sides thereof, preferably counterseated at 20, are imperforate panels 21 and fo-raminous screen or screen cloth sections 22 respectively. The panels 21 are reversed in their positions with respect to the frame in that at the outer side thereof this panel 21 is at the uppermost half of said frame, while at the inner side 40 of the frame the panel 21 is at the lower half thereof, which is also true with respect to the relationship of the screen sections 22 in that one section thereof at the inner side of the screen is uppermost and the other section at the outer side 45 of the screen is lowermost of the same. These panels and sections 21 and 22 at their meeting edges are overlapped and united with each other in any suitable manner as at 23 and 24 respectively. Thus, the arrangement of these panels and sections effects a ventilating space 25 within the open center of the ventilator frame. The panels 21 are preferably made from cel-o-glass, although the same may be made from any other suitable material as window pane glass, or trans-

parent, or translucent material. The panels 21 and the sections 22 are made fixed by suitable fasteners 26 engaged in the frame of the ventilator.

5 The air from without an enclosure enters the ventilator at the outer side thereof through the lower screen section 22, thence flows within the space 25 upwardly and delivered from this space through the section 22 at the inner side of the 10 ventilator frame and uppermost thereof. In this way direct draft upon the occupants of an enclosure or room from without will be avoided, and at the same time, maximum ventilation will be assured to the room or enclosure. The inclined 15 or sloping face 13 of the lowermost rail 11 of the ventilator frame functions as a watershed to avoid rain, sleet, or the like, from passing from without to within a room or enclosure through the said ventilator.

20 Arranged at the inner side of the ventilator frame are vertically disposed guides 27 for a slide 28 which constitutes a shutter or gate having a transparent or translucent center panel 29 preferably made from cel-o-glass. Now by adjustment of the slide 28 vertically of the ventilator frame to partially or completely cover the screen section 22 at the inner side of said frame, the ventilation through the ventilator can be regulated to an enclosure or room and thus this 30 slide 28 functions as a valve for the ventilator.

The slide 28 carries finger grips 30 to enable convenient and easy operation of the slide for the regulation of the ventilator in the use thereof.

35 The slide 28 at opposite ends thereof has fitted therewith abutment flanges 31 coacting with the guides 27 and in this way endwise displacement of the said slide will be avoided and, at the same time, the fitted slide through these flanges 31 will be held in a set position resultant from frictional 40 contact of the flanges 31 with the guides 27. In other words by the flanges 31 thereon the fitted slide will move true in the guides 27 and be held frictionally in an adjusted position.

By reason of the arrangement in the structural make-up of the ventilator, the room or enclosure cannot be viewed from without the same through said ventilator, and protection to occupants in this manner will be had, yet ventilation is insured to the enclosure or room and also it will be properly screened. 5

The ventilator admits light to an enclosure without rendering the same dark and such ventilator can be used with or without the extension 10 wings or pieces 14 as may be desired.

What is claimed is:

1. A ventilator of the character described comprising an open frame, tensioned extension wings at opposite ends thereof, and each telescopically 15 fitted therewith, imperforate panels fitted to the frame at opposite sides thereof, one of said panels covering the uppermost half of said frame and the other panel covering the lowermost half thereof, screen cloth fitted to the frame at opposite sides thereof and disposed in inverse relationship with respect to said panels, an imperforate slide fitted to one side of the frame and movable to covering position with relation to the screen cloth at that side of said frame, and guides 20 for the said slide and flanges on the slide for frictionally engaging the guides to hold the slide in an adjusted position.

2. A ventilator of the character described, comprising an open frame, imperforate panels 30 fitted to the frame at opposite sides thereof, one of said panels covering the uppermost half of said frame and the other panel covering the lowermost half thereof, screen cloth fitted to the frame at opposite sides thereof and disposed in 35 inverse relationship with respect to said panels, an imperforate slide fitted to one side of the frame and movable to covering position with relation to the screen cloth at that side of said frame, guides for the said slide, and flanges on 40 the slide for frictionally engaging the guide to hold the slide in an adjusted position.

PHILIP HERMAN.
